UNITED STATES PATENT OFFICE.

MILTON E. SMITH, OF SPOKANE, WASHINGTON.

RAIL-TIE STRUCTURE.

1,237,566.

Specification of Letters Patent. Patented Aug. 21, 1917.

Application filed March 13, 1916. Serial No. 83,887.

To all whom it may concern:

Be it known that I, MILTON E. SMITH, a citizen of the United States, residing at Spokane, in the county of Spokane and State of Washington, have invented certain new and useful Improvements in Rail-Tie Structures, of which the following is a specification.

This invention relates to improvements in rail tie structures.

It is one of the objects of this invention to mount the rails upon alined sleepers, and to tie the separated rail structures together by gage means in such a manner that the rails will be held to a true gage position with respect to each other.

A further object of the invention is to provide a gage bar with end flanges and supported by rail chairs on its ends, the rail chairs of each bar being provided with inwardly and outwardly facing rail engaging gage lugs for engaging one rail on the outside thereof and the other rail on the inside thereof, this construction providing for end to end alternation of the bars, so that the lugs of the chairs thereof will positively hold the rails to a true gage position.

A further object is to provide an improved form of sleeper, which is grooved or otherwise cut out in a manner to receive the ends of the gage bars and to act as supports for the rail chairs of the bars.

Other objects and features of my invention will be more fully described in connection with the accompanying drawing, and will be more particularly pointed out in and by the appended claims.

In the drawing:—

Figure 1 is a plan view of a rail tie structure embodying one form of my invention.

Fig. 2 is a sectional view on line 2—2 of Fig. 1.

Fig. 3 is a perspective view of one of the sleepers.

Fig. 4 is a perspective view of one end of a gage bar, showing one of the rail chairs.

Fig. 5 is a sectional view on line 5—5 of Fig. 3.

Fig. 6 is a sectional view on line 6—6 of Fig. 3.

Like characters of reference designate similar parts throughout the different figures of the drawing.

As illustrated, 1 and 2 designate one of a

plurality of pairs of alined sleepers for supporting rails 3 and 4. The sleepers are preferably formed of a cementitious material, which is adapted to be molded or cast, such as concrete, and as shown more particularly in Figs. 3, 5 and 6, the sleeper comprising an upper supporting face 5, which is reduced in length with respect to the length of the sleeper, the latter sloping off as indicated at 6. An inverted T-shaped slot or groove is formed longitudinally of the sleeper, the head portion 7 of the slot being lowermost and the stem portion 8 extending upwardly to the supporting face 5. Wearing plates 9 are preferably cast in the sleeper so as to prevent the gage bar from wearing the stem portion 8 of the groove or slot, as will hereinafter more fully appear. On the upper face of the sleeper are suitable recesses 10 in which cushioning elements or plates 11 are seated in a manner to lie flush with the supporting face 5. As will be seen more clearly by reference to Fig. 3, the cushioning plates or elements 11 which may be of wood, are reduced in length with respect to the supporting face 5 and are provided with inclined ends 12, which abut against correspondingly inclined ends of the recesses 10 in a manner to hold the cushioning plates in position. The cushioning plates may be cast or molded into the sleeper, or may be attached thereto after the sleeper is completed. Spike holes 13 are provided in the cushioning elements 11 and extend therethrough at an angle to the vertical. Spike sockets 14 are formed in the sleeper in a manner to register with the spike holes 13 of the cushioning plates 11. In order to enable the sleepers 1 and 2 to be interchangeably used for either rail, the T-shaped grooves extend completely through the sleepers, as will be seen by reference to Fig. 3.

Gage bars connect the opposed pairs of sleepers and each bar comprises a connecting portion 15 having flanges 16 projecting laterally therefrom at its ends, so that the cross section of each end will correspond to the cross section of the groove in the sleeper in which the end of the bar is telescopically fitted, the ends of the bars being T-shaped in cross section. The web portion 17 will engage the edges 18 of the wearing plates to prevent excessive wear of the upper portion 8 of the sleeper groove. On each end of each bar 1 form, preferably integrally

therewith, a rail chair 19 which is in the form of a flat plate adapted to rest upon the cushioning elements 11. The rail chair 19 is provided with rail flange engaging and 5 positioning ribs 20 between which the base flanges of the rails seat so as to initially dispose the rails at true gage. The rail chair on one end of each gage bar is shown provided with spike holes 21, disposed outwardly 10 from the rail seat between the ribs 20, while on the other end of the gage bar, or in other words, at the opposite chair, similar spike holes are provided but are located inside of the rail seat between the 15 ribs 20. Rail chair 19 is provided with an outwardly facing rail engaging gage lug 22, which is adapted to take over or overlap the inside flange of the left hand rail. The opposite chair 23 is provided with an inwardly facing rail engaging gage lug 24, which is disposed in a manner to overlap the outer flange of the right hand rail 4.

Now it will be seen by reference to adjacent gage bars in Fig. 1 that they are 25 laid or disposed in a manner to alternately reverse the chairs, or the positions of the chairs, of the gage bars so that lug 22 will engage the inside flange of rail 3 as regards bar *a*, whereas lug 24 of bar *b* will engage 30 the outside flange of rail 3. This end for end disposition of adjacent bars is carried out in such a manner that the rails will positively be held to a true gage position and against any spreading action.

35 From the foregoing description, it will be noted that so far as the structure is now described, the rails are positively connected or united with the gage bars, but the latter and the rails are not positively united with the sleepers, as regards endwise displacement with respect thereto.

Before the rails are laid, I loosely dispose spikes 25 and 26 in the alined sleepers and the same may be elevated slightly when 45 the rails are disposed in positive engagement with the gage bars and thereafter forced downwardly as shown in Fig. 2. Now it will be seen that the spikes extend through the holes in the rail chairs, and likewise 50 through the spike holes in the cushioning elements into the sockets of the sleepers, thereby positively uniting the connected rails and gage bar means with the sleepers to prevent any longitudinal play or displacement of the latter with respect to the 55 former and thereby insure a proper positioning of the rail chairs upon the cushioning elements. It will thus be seen that the spikes function the same as keys to operatively unite the sleepers with the rails and gage bars.

60 It will be seen that spikes 25 act in opposition to lugs 22 and that spikes 26 act in opposition to lugs 24 and that all the parts 65 are interchangeable and do not require

right and left disposition to carry out the hereinbefore described advantages. Thus it is possible to make all sleepers and all gage bars of identical formation with respect to each other.

70 It will be noted that the spikes are inclined from the vertical, all in the same direction, with the heads of the spikes nearest the rails, the inclination being such that the spikes cannot work out or be withdrawn 75 after the rails are in position.

It will also be noted that the spike holes 13 in the cushioning elements assist in holding the spikes to true positions without subjecting the sleeper sockets to undue wear. 80

It is believed that the advantages and utility of this invention will be clearly understood from the foregoing description, and while I have herein shown and described one specific form of my invention, 85 I do not wish to be limited thereto except for such limitations as the claims may import.

I claim:—

1. In a rail tie structure, alined sleepers 90 provided with inverted T-shaped grooves below and opening to their rail supporting tops and extending longitudinally through said sleepers, rail cushioning plates on said sleepers, a gage bar having flanged ends corresponding in cross-section to the cross-section of said grooves and having rail chairs formed integrally on the ends of said bar and seated on said cushioning plates, one chair of each bar having an inwardly facing 95 integral rail gage lug and the other chair of such bar having an outwardly facing integral rail gage lug whereby end to end alternation of adjacent gage bars will positively hold the rails to a true gage position, substantially as described.

2. In a rail tie structure, alined sleepers, provided with longitudinally disposed grooves therein, a gage bar having ends of a cross-section corresponding to the cross-section of said grooves and provided on its ends with rail chairs for support by said sleepers, cushioning elements interposed between said chairs and sleepers, one chair of each bar having an integral inwardly facing rail engaging gage lug and the other chair of such bar having an outwardly facing integral rail engaging gage lug whereby end to end alternation of adjacent gage bars will positively hold the rails to a true gage position, and spikes disposed on opposite sides with respect to said gage lugs and engaging the rails and extending through the chairs and cushioning elements into the sleepers to lock the parts together, the spikes of endwise opposite sleepers being inclined from the vertical in the same direction, substantially as described.

3. In a rail tie structure, alined sleepers, provided with longitudinally disposed 130

grooves therein, a gage bar having ends of a cross-section corresponding to the cross-section of said grooves and provided on its ends with rail chairs for support by said sleepers, one chair of each bar having an integral inwardly facing rail engaging gage lug and the other chair of such bar having an outwardly facing integral rail engaging gage lug whereby end to end alternation of adjacent gage bars will positively hold the rails to a true gage position, and spikes disposed on opposite sides of the rails with respect to said lugs and extending through the chairs and into the sleepers at an inclination to the vertical with the head ends of the spikes nearest the rails, substantially as described.

4. In a rail tie structure, alined sleepers, a gage bar provided on its ends with chairs formed integral therewith for support by said sleepers, one chair of each bar having an integral inwardly facing rail engaging gage lug and the other chair of such bar having an outwardly facing integral rail engaging gage lug whereby end to end alternation of adjacent gage bars will positively hold the rails to a true gage position, and devices engaging the rails and acting in opposition to the lugs and holding the chairs

and sleepers in prescribed relation, substantially as described.

5. In a rail tie structure, alined sleepers for supporting opposite rails, a gage bar having rail chairs on its ends for support by said sleepers and integral rail engaging gage lugs, and spikes engaging the rails in opposition to said lugs and extending through said chairs and into said sleepers at the same angle to the vertical with the heads of said spikes nearest said rails, substantially as described.

6. In a rail tie structure, alined sleepers for supporting opposite rails, a gage bar having rail chairs on its ends for support by said sleepers and the chair on one end having an inwardly facing rail gage lug and the chair on the other end of said bar having an outwardly facing rail gage lug, a spike inclined to the vertical outwardly for engagement with the inside of the rail engaged by said inwardly facing lug, and a spike inclined inwardly from the vertical for engagement with the outside of the rail engaged by the outwardly facing gage lug, said spikes extending through the chairs and into the sleepers, substantially as described.

In testimony whereof I affix my signature.
MILTON E. SMITH.
